DESIGN FOR A BAR TRAY OR THE LIKE

Joshua Gordon Lippincott, Scarsdale, N. Y.

Application January 12, 1940, Serial No. 89,442

Term of patent 7 years

To all whom it may concern:

Be it known that I, Joshua Gordon Lippincott, a citizen of the United States and a resident of Scarsdale, in the county of Westchester and State of New York, have invented a new, original, and ornamental Design for a Bar Tray or the like, of which the following is a specification, reference being had to the accompanying drawing, forming a part thereof.

Fig. 1 is a top plan view of the bar tray or the like, showing my design; and

Fig. 2 is a side elevational view thereof.

I claim:

The ornamental design for a bar tray or the like, substantially as shown.

JOSHUA GORDON LIPPINCOTT.
